UNITED STATES PATENT OFFICE

155,588

DESIGN FOR A NIGHT LIGHT

Theodore R. Finke, Euclid, Ohio

Application February 4, 1949, Serial No. 677

Term of patent 7 years

(Cl. D48—20)

To all whom it may concern:

Be it known that I, Theodore R. Finke, a citizen of the United States, residing at Euclid, county of Cuyahoga, and State of Ohio, have invented a new, original, and ornamental Design for Night Light, of which the following is a specification, reference being had to the accompanying drawing, forming a part thereof.

Fig. 1 is an elevational view of a night light, showing my new design; and

Fig. 2 is a top plan view of the night light.

Fig. 3 is a cross sectional view taken on the line 3—3 of Fig. 1.

I claim:

The ornamental design for a night light, substantially as shown.

THEODORE R. FINKE.
